CLAIM

The ornamental design for a radiator wrench, as shown and described.

DESCRIPTION

FIG. 1 is a perspective view of the radiator wrench;
FIG. 2 is a front view of the radiator wrench;
FIG. 3 is a back view of the radiator wrench;
FIG. 4 is a left side elevation view of the radiator wrench;
FIG. 5 is a right side elevation view of the radiator wrench;
FIG. 6 is a top view of the radiator wrench; and,
FIG. 7 is a bottom view of the radiator wrench.

The broken lines shown in the drawings are for the purpose of illustrating portions of the article that form no part of the claimed design.
